SLIDE BOLT UNIT

Erling P. Bugge, P.O. Box 36183, Wilshire-La Brea
Station, Los Angeles, Calif.

Filed Nov. 14, 1960, Ser. No. 62,836

Term of patent 7 years

(Cl. D50—5)

FIGURE 1 is a perspective view of a slide bolt unit embodying my new design, the spacing between keeper and latch bolt being exaggerated for clarity of illustration;

FIGURE 2 is a side elevational view, but showing the bolt and keeper engaged;

FIGURE 3 is an end elevational view, from the end having the keeper;

FIGURE 4 is a bottom plan view of the engaged bolt and keeper; and

FIGURE 5 is an elevational view taken from the end having the latch bolt handle.

I claim:

The ornamental design for a slide bolt unit, substantially as shown.
